UNITED STATES PATENT OFFICE

2,051,311

HOT WATER HEATER

Robert Edwin Moore, Chicago, Ill., assignor to
 Bell & Gossett Company, Chicago, Ill., a corporation of Illinois

Application January 4, 1935, Serial No. 394

2 Claims. (Cl. 236—19)

My present invention relates to the provision of a non-liming hot water heater with temperature control and, as the above designation implies, has for its object, first, the provision of a hot water heater in which water containing salt of calcium in solution may be heated without causing a deposition of lime upon the heater, and, second, the provision of a heater in which the maximum temperature to which the water can be heated is controlled or regulated.

I have accomplished these objects by means of the structure illustrated in the accompanying drawing, in which—

Fig. 1 is a schematic view of a boiler and a hot water storage tank with a water heater embodying my invention assembled with and forming the connection between the boiler and the tank.

Fig. 2 is a central vertical elevation through the heater casing.

Fig. 3 is a fragmental detail, partially in section, of the means employed for adjusting the apparatus to secure the desired maximum heating temperature.

Similar reference characters refer to similar parts throughout the respective views.

The water heater or heat transfer device consists of a cylindrical casing 5 having, preferably, a semi-spherical bottom 6, the center 7 whereof is tapped and threaded for receiving the piping constituting the return 8 to the boiler. The top of the casing 5 is a removable closure plate 9 held to the casing by machine bolts 10, or other suitable means. Installed within the casing 5 is a coil 11, preferably of copper because of its heat conducting properties, which coil 11 is connected through ports 12 in the casing by means of tubes 13 with the hot water storage tank 14. The form and arrangement of the casing 5, coil 11 and connection between the coil 11 and the hot water storage tank 14 are in accordance with present standard practice.

Instead, however, of connecting the casing 5 through ports 15 and 16 directly with the boiler 17 I connect the ports 15 and 16 with the tubular ends 18 and 19 of a fitting comprising such tubular ends connected by a tubular body portion 20. The tubular body portion 20 is extended beyond the tubular end 19 and the end of such extension is closed by a clean-out plug 21.

Mounted and secured at the lower end of the tubular body portion 20 is a bi-metallic thermosensitive strip of metal 22. The strip of metal 22 passes through the bore in the member 20 beyond the central line or axis of the tubular

end 18 and adjacent the end thereof is provided with a valve 23 which co-operates with the valve seat 24 located in the tubular end portion 18. Connecting with the outer end of tubular portion 18 is a pipe 25 which leads to the boiler 17 at a point adjacent but below the water line thereof. About the middle of the tubular body portion 20 is provided a bore 26 in which is slidably mounted the stud of a bridle member 27 through which the bi-metallic strip 22 passes. A screw 28 and a lock nut 29 are provided by means of which the position of the bridle 27 may be adjusted which will control the temperature at which the bi-metallic strip 22 will raise the valve 23 from its seat 24. The boiler water is caused to circulate through the casing 5 by gravity inasmuch as when the water condenses by contact with the coil 11 and becomes heavier and falls it will be returned to the bottom of the boiler 17 and hot water will flow into the casing 5 through the pipe 25.

The bridle 27 is adjusted so that when the boiler water flowing into the casing 5 has attained the hottest desired temperature the bi-metallic strip will flex so as to seat the valve 23 upon its seat 24, but when the temperature of water in the casing 5 is below the hottest desired temperature the bi-metallic strip 22 will be flexed in the opposite direction so as to raise the valve 23 from its seat 24 and permit the hot boiler water to enter the casing 5.

Much, if not all, of water available for service distribution is what is known as "hard" and one reason for the hardness in water is that the water contains carbon dioxide gas in solution and water with carbon dioxide gas in solution is capable of dissolving calcium carbonate. When the water is heated the carbon dioxide gas is driven off and the calcium carbonate is deposited.

It is found, however, that if the water is not heated above 135° or 140° F. the carbon dioxide gas will not be driven off and the calcium carbonate will not be deposited.

The water to be heated passing through the coil 11 can never be raised to the temperature of the boiler water circulating about the coil 11 in the casing 5, but the water to be heated will raise to about 10° to 15° of the temperature of the boiler water so that if the bi-metallic strip is set to open the valve 23 at say 145° or 150° F. the water in the coil 11 will never be heated to a point where the lime will be deposited. Moreover, service water heated above 135° or 140° F. is liable to start the joints and the packing in the hot water

distribution system and is dangerous, or liable to be dangerous, to the person using the water.

While a hot water heater of this kind is not an excessive absorber of the heat from the boiler water it, nevertheless, absorbs some of the heat and my present invention limits such absorption strictly to the amount necessary to bring the service water supply to the temperature required. By making the bi-metallic strip 22 substantially as long as the coil 11 it is responsive to and actuated by the temperature of all of the water which is acting upon the coil 11 and not merely the hottest portion thereof located adjacent the valve 23.

Having described my invention what I claim is new and desire to secure by Letters Patent is:

1. In combination with a hot water heater comprising a casing adapted to be connected to a boiler for securing a circulation of boiler water therethrough and having a heat transfer coil adapted to be connected with a service water supply installed within said casing, a fitting having transverse end channels therein adapted respectively to be included in the conduit from the casing to the boiler and to the casing at a point adjacent the bottom thereof, and a connecting

means with a channel establishing communication between said end channels in which communicating channel is mounted a bi-metallic element, and a valve carried by said bi-metallic element cooperating with a valve seat for controlling the passageway from the boiler to the casing. 5

2. In combination with a hot water heater comprising a casing adapted to be connected to a boiler for securing a circulation of boiler water therethrough and having a heat transfer coil adapted to be connected with a service water supply installed within said casing, a fitting having transverse end channels therein adapted respectively to be included in the conduit from the casing to the boiler and to the casing at a point adjacent the bottom thereof, and a connecting member having a channel establishing communication between said end channels in which communicating channel is mounted a bi-metallic element, a valve carried by said bi-metallic element co-operating with a valve seat for controlling the passageway from the boiler to the casing, and means for adjustably modifying the flexing of said bi-metallic element. 15 20 25

ROBERT EDWIN MOORE.
